UNITED STATES PATENT OFFICE.

FRANK A. E. MARSH, OF LYNN, MASSACHUSETTS, ASSIGNOR TO UNITED SHOE MACHINERY CORPORATION, OF PATERSON, NEW JERSEY, A CORPORATION OF NEW JERSEY.

FINISHING MACHINE.

Application filed January 5, 1925. Serial No. 578.

To all whom it may concern:

Be it known that I, FRANK A. E. MARSH, a citizen of the United States, residing at Lynn, in the county of Essex and Common-

5 wealth of Massachusetts, have invented cer-
tain Improvements in Finishing Machines,
of which the following description, in con-
nection with the accompanying drawings, is
a specification, like reference characters on
10 the drawings indicating like parts in the
several figures.

This invention relates to finishing ma-
chines and more particularly to burnishing
tools for such machines of the type employ-
15 ing sectional work-rubbing members.

One conspicuous use of finishing machines
is in burnishing the peripheries of leather
heels of boots and shoes, and for this pur-
20 pose machines have been extensively em-
ployed which utilize a burnishing tool made
up of sectional, metallic, work-rubbing mem-
bers. As commonly constructed these tools
have comprised sectional work-rubbing
25 members which have been mounted either
rigidly or pivotally upon the free ends of
flat springs. These springs have been se-
cured at their other ends upon a carrier
sleeve which in turn was mounted upon a
30 power-driven shaft. Such an arrangement
allowed the various sections of the iron to
have in-and-out and twisting movement to
accommodate themselves to the work and to
avoid making tool marks. When such ma-
35 chines are used by skilled operators, they are
highly successful, but when put into the
hands of unskilled and careless operatives,
objection has been raised because of the
noise created when excessive pressure is ap-
40 plied to the work and because of the break-
age of parts due to the application of such
pressure.

In view of the above, one object of the
present invention is to provide an improved
finishing tool arranged to minimize the noise
45 of and breakage in a tool of this character
without detracting from the quality of the
work performed.

To this end a feature of the invention re-
lates to an arrangement for limiting the
50 in-and-out movement of the spring-sup-
ported work-rubbing members so that such
movement is practically eliminated, thus re-
ducing the noise of the tools during the use
of such machines and at the same time mini-
55 mizing breakage of the rubbing elements.

Preferably, a cushion of relatively soft ma-
terial is interposed between the spring-sup-
ported work-rubbing members and the car-
rier member.

Another feature of the invention relates 60
to an arrangement designed to give the work-
rubbing members freedom for torsional
movement while limiting their in-and-out
movement. For this purpose, as illustrated,
the interposed cushion is provided with 65
longitudinal flutes which are placed in a
predetermined relation to the sections of the
work-rubbing members and preferably are
so placed that the flutes lie directly beneath
the sections. The bases of the illustrated sec- 70
tions are provided with curved surfaces co-
acting with said flutes to allow a twisting
movement of the tool sections on the ends
of the flat springs in order to render the
tool less rigid and enable it to conform more 75
nearly to the irregularities of the particular
piece of work to which it is applied. As in
tools of this general character previously
used, an overhanging retaining ring co-oper-
ates with the outer ends of the bases of the 80
sectional work-rubbing members to limit the
outward movement thereof under the action
of centrifugal force and, in my improved
construction, the co-operating outer surfaces
upon the bases of the work-rubbing mem- 85
bers are curved in order that the flexing of
their spring supports may not be interfered
with by reason of this contact between the
bases and the retaining ring.

In finishing machines employing burnish- 90
ing tools of this character the tool is some-
times heated electrically by means of a car-
tridge unit carried within the tool-carrying
shaft at a point adjacent to the burnishing
tool. In view of the fact, however, that such 95
tools, as previously constructed, have been
provided with a space between the carrier
sleeve of the tool and the tool-carrying sec-
tions, the heat of the electric unit could only
be transmitted conductively to the sections 100
of the tool through the flat springs. Such a
method, although effective, is inefficient, and
another object of the invention is to provide
improved means for transmitting the heat of
such an electric unit conductively to the sec- 105
tions of the burnishing tool.

With this object in view the fluted ring
used, as above-described, in the burnishing
tool for another purpose is made of metal
having a high heat conductivity and contacts 110

directly with both the tool sections and the carrier sleeve. As a result the heat of the electric unit is transmitted to the sections of the burnishing tool with considerable efficiency because of this direct conductive path between the sections of the tool and the electric unit.

These and other features of the invention will be more readily understood from a consideration of the following specification taken in connection with the accompanying drawings in which:

Fig. 1 is a perspective view of a burnishing tool, embodying my invention, viewed from the rear and having one section removed;

Fig. 2 is a perspective view of a single section of the burnishing tool together with its supporting spring;

Fig. 3 is a transverse section on the line 3—3 of Fig. 4; and

Fig. 4 is a longitudinal section through the center of the burnishing tool and its supporting shaft.

Tools of the general character described, in order that they may conform to the curvature of a particular style of heel which is to be burnished, for example, are made interchangeable so that, in any particular tool, the individual work-rubbing members may be so curved that the resulting periphery of the tool has the desired shape. To this end the individual work-rubbing members 10, having curved, outer, work-contacting surfaces 12, are supported upon a carrier member 14 formed as a sleeve. This carrier sleeve is enlarged at the end remote from the work-rubbing tools and the enlarged end is grooved at 16 to receive flat springs 18 which are held in place by screw studs 20. This method of mounting the springs on the carrier sleeve prevents twisting around the point of attachment with a resultant undesired change in the relative spacing of the various sections of the work-rubbing member. As best seen in Fig. 2, each of the work-rubbing members 10 is provided with a shank 22 interposed between the work-rubbing portion and a base portion 24. This base portion is secured to the end of the spring 18 by means of rivets 26 passing through an extension or sub-base 28 secured to the under side of the end of the spring. The inner rivet passes through the spring 18 as well. This extension 28 is provided with a rounded under surface and has a reduced end portion which is curved, as shown at 30, for a purpose to be later explained. A correspondingly reduced portion of the base 24 is curved at 32 in a reverse direction. At the outer end of the carrier sleeve 14 a guard ring 34 is provided having an overhanging portion which cooperates with the reduced extension of the base having the curved upper surface 32 and

prevents the work-rubbing members from flying out under the action of centrifugal force.

Between the carrier member 14 and the spring extensions 28 a soft metal ring 40 acting as a cushion of relatively soft material is mounted and held in close contact with the carrier sleeve by rivets 44 of a similar metal. This ring 40 is provided with longitudinal flutes 43 which, in the preferred form of the invention illustrated herein, are disposed immediately beneath the rounded extensions 28 on the under side of the flat springs. As will be noted from Fig. 3, the curvature of the surface 30 is on a slightly smaller radius than the radius of curvature of the flutes 43 of the ring 40 so that a rocking or twisting action is allowed to the individual work-rubbing members to enable them to conform to irregularities of the work while at the same time inward movement is restricted or practically eliminated as they rest on the cushion ring 40. This twisting movement is not interfered with by the overhanging guard 34 because of the curved surfaces 32 upon the upper side of the outer ends of the bases of the work-rubbing members. The clearance between these upper outer ends of the bases of the work-rubbing members and the inner side of the retaining ring 34 will usually be limited to a few thousandths of an inch.

When such a tool is mounted in a finishing machine in which it is desired to heat the tool electrically, it is secured on a reduced portion of a tool-carrying shaft 50, the outer end of which is split and expanded by means of a tapered plug 52 which thereby holds the tool in position. Heat is supplied to the tool mounted in this fashion by means of a cartridge unit 54 carried in the hollow of the shaft and current is supplied to this unit in a manner well understood in the art by means of conductors running through the hollow shaft and connected individually to collector rings 56 which are insulated from the shaft as indicated at 58 and to which current is supplied by means of brushes 60. A guard member, indicated at 62, is supported upon a fixed portion 64 of the frame of the machine and covers the springs of the burnishing tool without restricting access to the work-rubbing surface thereof.

The described construction will be seen to provide a finishing machine in which the burnishing tool may be electrically heated with relatively high efficiency by reason of the direct conductive metallic path provided for the transfer of heat from the electric cartridge unit to the work-rubbing sections of the burnishing tool. As the work is applied to the work-rubbing surfaces 12, the individual sections of the tool will, although they are restricted as to inward and outward movement, have a tilting movement as the

curved surfaces 30 roll in the flutes 43 of the supporting ring. To improve this action, the flat springs 18 are preferably made somewhat lighter than has been found desirable in the constructions heretofore employed. Because of the fact that there is little opportunity for in-and-out movement of the individual sections and because each of these sections rests against a relatively soft metal cushion ring, the noise sometimes found in connection with such tools is practically eliminated.

Having described the invention, what I claim as new and desire to secure by Letters Patent of the United States is:

1. A finishing tool comprising a carrier member, sectional work-rubbing members resiliently attached to said carrier member at a point remote from the point of application of the work, and a cushion of relatively soft material interposed between the resiliently supported work-rubbing members and the carrier member beneath the point of application of the work.
2. A finishing tool comprising a carrier member, sectional work-rubbing members, flat springs attached to said carrier member at one end and supporting the sectional members at their other ends, and a cushion of relatively soft material interposed between the free ends of the springs and the carrier member.
3. A finishing tool comprising a carrier member, sectional work-rubbing members resiliently attached to said carrier member, and means for substantially eliminating in-and-out movement of said members constructed and arranged to permit twisting movement thereof thereby allowing the iron to conform to the work.
4. A finishing tool comprising a carrier member, sectional work-rubbing members, flat springs connected to said carrier member at one end and rigidly attached to and supporting said work-rubbing members at their other ends, and means for limiting the in-and-out movement of the work-rubbing members constructed and arranged to allow tilting of said work-rubbing members with a consequent twisting of said springs.

5. A finishing tool comprising a carrier member, resilient supports attached to said member, sectional work-rubbing members carried on said resilient supports at a point remote from their point of attachment, and a fluted ring interposed between said carrier sleeve and said resilient supports at the free ends of the resilient supports constructed and arranged with a flute in a predetermined relation to each section of the work-rubbing member so that said sections may tilt to conform the iron to the work without allowing inward movement of the sectional members.

6. A finishing tool comprising a carrier

member provided with a longitudinally fluted ring at one end thereof, and sectional work rubbing members mounted upon flat springs fastened on said carrier member at a point removed from the fluted ring and arranged in a predetermined relation to the flutes thereof, said work-rubbing members being provided with a rounded surface co-operating with said fluted ring to allow tilting of the sections of the iron while restricting the inward movement thereof.

7. A finishing tool comprising a carrier member, a longitudinally fluted ring adjacent to one end of said carrier member, flat supporting springs secured to said carrier member adjacent to its other end, and sectional work-rubbing members having base portions secured to the free ends of said springs, said base portions being provided with rounded surfaces co-operating with the fluted ring to allow tilting movement of the sections of the iron and arranged in predetermined position with respect to said flutes thereby to limit the inward movement of the work-rubbing members.

8. A finishing tool comprising a carrier member, a longitudinally fluted ring adjacent to one end of said carrier member, flat supporting springs secured to said carrier member adjacent to its other end, sectional work-rubbing members having base portions secured to the free ends of said springs, said base portions being provided with rounded upper and under surfaces, said under surfaces co-operating with the fluted ring to allow tilting movement of the sections of the iron and arranged in predetermined position with respect to said flutes thereby to limit the inward movement of the work-rubbing members, and an overhanging retaining ring co-operating with the rounded upper surfaces on the bases of said sectional members to limit the outward movement thereof while not restricting the tilting movement of the sections.

9. In a machine of the character described, a hollow tool-carrying shaft, a heating unit disposed in the hollow of said shaft, a finishing tool provided with a carrier sleeve disposed on said shaft adjacent to said heating unit, sectional work-rubbing members resiliently supported on said sleeve, and a metallic ring of high heat conductivity disposed between said sectional work-rubbing members and the carrier sleeve at a point adjacent to the position of the heating unit to form a conductive path of low resistance directly from the heating unit to the work-rubbing members.

10. A finishing tool comprising a carrier member, sectional work-rubbing members, and means for supporting said work-rubbing members upon said carrier member constructed and arranged to allow limited

movement of said work-rubbing members circumferentially while substantially eliminating radial movement thereof.

11. A finishing tool comprising a carrier member, and sectional work-rubbing members flexibly supported on said carrier member and normally held against radial movement inwardly under pressure of the work.

10. 12. A finishing tool comprising a carrier member, and sectional work-rubbing members flexibly supported on said carrier member and normally held against radial movement inwardly under pressure of the work

and also held against outward radial movement under the action of centrifugal force.

13. A finishing tool comprising a carrier member, sectional circumferentially extending work-rubbing members supported by substantially radial shanks, and means for resiliently supporting said shanks on said carrier member constructed and arranged to allow the shanks to twist in a circumferential direction while substantially preventing radial movement thereof.

In testimony whereof I have signed my name to this specification.

FRANK A. E. MARSH.
